UNITED STATES PATENT OFFICE.

HENRY S. LOUD, OF NEW YORK, N. Y.

METHOD OF TREATING POROUS BODIES WITH LIQUID PRESERVATIVE.

1,151,205.

Specification of Letters Patent. Patented Aug. 24, 1915.

Application filed June 8, 1915. Serial No. 32,938.

To all whom it may concern:

Be it known that I, HENRY S. LOUD, a citizen of the United States, residing in the borough of Manhattan, city, county, and State of New York, have invented new and useful Improvements in Methods of Treating Porous Bodies with Liquid Preservative, of which the following is a specification.

10 My invention is an improvement in methods of impregnating wood and other porous bodies with preservative liquid under pressure, and consists in placing the body to be treated in a vessel and then hermetically sealing the vessel, and then forcing preservative liquid into the vessel in such manner as to intermittently drench the surface of the article, thus create a succession of covering films of liquid thereon, 15 and meanwhile to increase the pressure of air contained in or introduced into the vessel upon said films, whereby commingled preservative and air are forced together under equal pressure into the pores, voids, 20 interstices and tissues of the article until the article is sufficiently impregnated or is eventually submerged in the accumulated liquid to secure additional impregnation. In some cases it is found desirable to first 25 subject the article to be treated to a vacuum and then to drench the same with the liquid under increasing air pressure.

When the desired degree of pressure has been reached and the requisite amount of preservative forced into, and diffused through the article, the inflow of fluid is cut off, and the pressure within the vessel reduced to, or below, atmospheric, for a period sufficient to allow the excess liquid in the 35 article to be ejected which usually requires not more than forty-five minutes, and then the surplus liquid is withdrawn under such reduced pressure.

In the accompanying diagrammatic drawing is shown an apparatus adapted for carrying out my improved process, in which—

40 A represents a suitable horizontally disposed cylinder in which a railway tie 2 is inserted for treatment. Longitudinally disposed within the cylinder are spray pipes 3 and 4 supported, if necessary, by means of arms or brackets 5, one arranged above and

the other below the tie, having jets or openings 6, for distributing the contents of the 55 pipes over the surfaces of the tie.

7 is a feed pipe leading to the distributing pipes, and connected by means of the valved pipe 8 with a source of preservative supply.

9 is an injector nozzle connected by the 60 valved pipe 10 with a source of compressed air supply.

11 is a vent pipe, controlled by the valve 12 to connect the bottom of the cylinder with vacuum producing means 13 in a pressure gage, and 14 is a safety valve or valve-controlled air vent.

15 is a valved pipe connecting the bottom of the cylinder with the source of preservative supply.

70 The manner in which the described apparatus carries out my improved process is as follows: The article to be treated, in this case a railway tie, is inserted into the cylinder which is then closed and hermetically sealed. The valve 12 being closed the preservative liquid is conveyed from its source of supply through the pipe 8 into the spray pipes 3 and 4 either under liquid pressure alone or with the additional pressure of compressed air introduced through the injector 9, whereby the preservative is delivered in a fine or atomized spray upon and against the surfaces of the tie thoroughly drenching the same and creating 85 thereover a film of flowing liquid. Meanwhile the air within and delivered into the cylinder is increasingly compressed whereby it forces preservative from this film into the pores and tissues of the tie ahead of, 90 and commingled with it.

95 After the initial drenching of the article the valve 10 in pipe 8 is alternately closed and opened again preferably at short intervals, so as to increase the relative proportion of air injected into the article as compared with a continuous flow of liquid. This penetration of the two fluids into the tie may be likened to successive minute pittings of liquid and air whereby the preservative is forced deeply into, and diffused throughout, the material.

100 It is obvious that in the carrying out of this process the degree of pressure, respective volumes of liquid and air forced into 105 the tie, the length of time employed, &c.,

may be varied as desired according to the qualities of the material being treated or to meet other specific requirements. When the desired volume of commingled preservative and air has been forced into the tie under the requisite pressure the tie may be allowed to be submerged by the accumulating liquid and such additional pressure applied thereto as may be required to secure the injection of a desired greater total amount of liquid. Then the inflow of fluid is cut off and the valve 12 in the pipe 11 is opened to draw off the liquid and air under vacuum, thus completing the operation. Obviously the inflow of liquid as above set forth might submerge the tie before the requisite amount of commingled preservative and air has been forced into the tie, in which case submergence is meanwhile prevented by allowing the excess liquid to flow back through the pipe 15 to its source of supply while maintaining or increasing the pressure within the cylinder.

While I have shown and described a cylinder with a single tie, it is obvious that a larger cylinder may be employed and a plurality of ties treated therein.

In order to assure absolute uniformity in the treatment of the bottom of the tie with that of the top portion, or the bottom tie of a plurality with the top one, during the period of submergence of the tie, or ties, the pressure within the cylinder is maintained without increase by permitting a sufficient amount of the contained air to escape through the vent valve 14, this valve being closed after submergence has been reached, after which the pressure will continue to increase to the desired limit.

Obviously, the amount and pressure of the accumulated air in the vessel may be regulated by means of the vent or safety valve 14.

Having thus described my invention, what I claim and desire to secure by Letters Patent is:—

1. The method which consists in intermittently covering a porous article with a flowing film of liquid, and surrounding such article with air under increasing pressure.

2. The method which consists in intermittently covering a porous article with a flowing film of liquid, surrounding such article with air under increasing pressure, and then cutting off the inflow of liquid, reducing the air pressure, and drawing off the surplus liquid under such reduced pressure.

3. The method which consists in intermittently drenching a porous article with liquid in the presence of air under progressively increasing pressure.

4. The method which consists in subjecting a porous article to subatmospheric pressure, then intermittently covering it with a

flowing film of liquid, and meanwhile subjecting the article to air under increasing pressure.

5. The method which consists in first subjecting a porous article to a vacuum, then intermittently drenching it with liquid under progressively increasing air pressure.

6. The method which consists in subjecting a porous article to a vacuum, then intermittently covering the article with a flowing film of liquid, and meanwhile surrounding the article with air under increasing pressure, then cutting off the inflow of liquid, reducing the air pressure, and drawing off the surplus liquid under such reduced pressure.

7. The method which consists in subjecting a porous article to a vacuum in a closed vessel, then intermittently covering the article with a flowing film of liquid, and meanwhile increasing the air pressure in said vessel and permitting the surplus liquid accumulated in the vessel to drain away to prevent submergence of the article, then allowing the surplus liquid to accumulate and submerge the article without increasing the air pressure, then again increasing the pressure, then cutting off the inflow of liquid, reducing the pressure, and drawing off the surplus liquid under such reduced pressure.

8. The method which consists in subjecting a porous article to a vacuum in a hermetically sealed vessel, then intermittently covering the article with a flowing film of liquid, and meanwhile increasing the air pressure in said vessel, then cutting off the inflow of liquid, and reducing the air pressure for a period sufficient to allow the surplus liquid in the article to be ejected, and drawing off such surplus liquid under such reduced pressure.

9. The method of impregnating wood and other porous material with a liquid which consists in confining the article in a hermetically sealed vessel, then intermittently drenching the material with the liquid to form a covering film, meanwhile subjecting said material to increasing air pressure, whereby the liquid of said film is forced into the pores, voids and interstices of the material in advance of and commingled with the air, and then permitting the accumulated liquid to submerge the material and increasing the pressure.

10. The method of impregnating wood and other porous material with a liquid which consists in confining the article in a hermetically sealed vessel, then intermittently drenching the material with the liquid to form a covering film, meanwhile subjecting said material to increasing air pressure, whereby the liquid of said film is forced into the pores, voids and interstices of the material in advance of and com-

mingled with the air, and then permitting the accumulated liquid to submerge the material and increasing the pressure, then cutting off the inflow of fluid and then reducing said pressure and drawing off the liquid under such reduced pressure.

11. The method of impregnating wood and other porous material with a liquid which consists in confining the material in a 10 hermetically sealed vessel, then intermittently drenching the material with the liquid to form a covering film, meanwhile subjecting said material to increasing air pressure and permitting the accumulating 15 liquid in the vessel to flow out of the vessel to prevent submergence of the article until the desired amount of commingled air and liquid has been injected into the material, then shutting off the outflow of liquid from 20 the vessel to permit complete submergence of the material without increase of pressure, then increasing the pressure to the desired limit.

12. The method of impregnating wood and other porous material with a liquid 25 which consists in confining the material in a hermetically sealed vessel, then intermittently drenching the material with the liquid to form a covering film, meanwhile subjecting said material to increasing air 30 pressure and permitting the accumulating liquid in the vessel to flow out of the vessel to prevent submergence of the article until the desired amount of commingled air and liquid has been injected into the material, 35 then shutting off the outflow of liquid from the vessel to permit complete submergence of the material without increase of pressure, then increasing the pressure to the desired limit, then cutting off the inflow of 40 liquid, reducing the pressure and drawing off the free liquid under such reduced pressure.

Signed at New York, county and State of New York, this 7th day of June, 1915.

HENRY S. LOUD.
